SUCTION NOZZLE

Axel Albert Forsberg, Stockholm, Sweden, assignor to Electrolux Corporation, New York, N. Y., a corporation of Delaware

Application March 11, 1939, Serial No. 261,273
In Sweden March 12, 1938

4 Claims. (Cl. 15—156)

The present invention relates to suction nozzles and more particularly to suction nozzles which may be used for a plurality of purposes.

In accordance with this invention an improved nozzle is formed with separate parts which may be readily separated for cleaning different materials. Also the parts are secured together in a manner to facilitate assembly and disassembly of the parts and to permit movement of one part with respect to another.

What I consider to be novel and my invention may be better understood by reference to the following specification and appended claims when considered in connection with the accompanying drawing in which:

Fig. 1 is a side elevation of my improved nozzle;

Fig. 2 is a sectional view taken along the line 2—2 of Fig. 1;

Fig. 3 is a detailed sectional view on an enlarged scale of a portion of the nozzle;

Fig. 4 is a perspective view of a tubular sleeve;

Fig. 5 is a detailed view of a modified form of sleeve; and

Fig. 6 is a side elevation of a part of the nozzle with the sleeve partly inserted on it.

Referring to the drawing, 10 indicates a nozzle body with a tubular extension 11 which is adapted to be connected to a vacuum cleaner or other suction device as by means of a flexible hose 12 shown in dotted lines. Body 10 flares outwardly from the extension 11 forming a channel 13 communicating with a narrow elongated opening 14 at the opposite end. In body 10 at each side of the opening 14, grooves 15 are provided adapted to receive the edges of a tubular sleeve 16. Sleeve 16 is provided with an opening 17 extending from one end to the other adapted to accommodate the end of body 10. The opening 17 may terminate short of one end of sleeve 16 forming a portion 18 of cylindrical shape as shown in Fig. 5. At the side of sleeve 16 opposite from the opening 17, a suction opening 19 is provided. Sleeve 16 is preferably inserted on part 10 by sliding it over the end as shown in Fig. 6 with the edges adjacent the opening 17 fitting in the grooves 15. However it may be found desirable to form sleeve 16 of an elastic material so that it may be snapped over the end of body 10. Sleeve 16 forms a chamber 20 at the opening 14 of body 10 communicating with suction opening 19 and channel 13. Extensions 21 are provided from body 10 at each end of opening 14 extending at right angles to the axis of sleeve 16.

A nozzle mouth 22 is provided with an elongated suction opening 23 and adapted to be connected to the body 10. Nozzle mouth 22 is provided with surfaces 24 conforming in shape to the sleeve 16 as best indicated in Fig. 3. Projecting portions 25 extend along the sides of extensions 21 of body 10. Nozzle mouth 22 is secured to body 10 by means of bolts 26 extending through openings in projecting portions 25 and in threaded engagement with extensions 21. Relative movement between the body 10 and part 22 is permitted on the horizontal axis of bolts 26.

In the assembly of the complete nozzle the sleeve 16 is first inserted over the end of body 10 and then the nozzle mouth 22 located in position and secured to the body 10 by the bolts 26. The completely assembled nozzle is designed primarily for the cleaning of rugs or other surfaces. The articulated connection between the body 10 and nozzle mouth 22 permits access beneath low pieces of furniture. If it is desired to clean draperies, curtains or the like, the part 22 may be removed from the body 10 by removing the bolts 26. The sub-assembly of the body 10 and sleeve 16 is then used as an independent nozzle for cleaning such material.

What I claim is:

1. A duplex suction nozzle including a body part flared outwardly at one end and having an elongated opening, a tubular part formed integrally with said body communicating with the interior of the body and adapted to receive means for connecting the nozzle to a source of suction, a sleeve of arched shape slidable over the elongated opening with edges received in grooves of said body and having a suction opening extending substantially throughout its length for cleaning upholstered furniture and the like, and a nozzle mouth detachably secured to said body whereby the nozzle is converted into a rug cleaning device.

2. A duplex suction nozzle including a body having an elongated opening at one end, extensions from said body at each end of said opening extending at right angles to the lengthwise extent of said opening, a sleeve of arched shape slidable over the opening of said body with its edges received in grooves in the body and having a suction opening extending substantially throughout its length, said extensions forming end walls for a chamber inclosed by said sleeve for cleaning upholstered furniture and the like, and a nozzle mouth part detachably secured to said body and having an elongated suction opening communicating with the suction opening of

said sleeve whereby the nozzle is converted into a rug cleaning nozzle.

3. A duplex suction nozzle including a body having a tubular part adapted to be connected to a source of suction and a flared end having an elongated opening; a sleeve of arched shape slideable over the elongated opening of said body with its edges received in grooves in the body, forming a chamber communicating with the interior of the body, and having a suction opening extending substantially throughout its length for cleaning upholstered furniture and the like; extensions closing the ends of said sleeve; and a nozzle mouth part detachably secured to said body communicating with the interior of said body, and having an elongated suction opening whereby the nozzle is converted into a rug cleaning nozzle.

4. A duplex suction nozzle including a body

having a tubular part adapted to be connected to a source of suction and a flared end having an elongated opening; a sleeve of arched shape slideable over the elongated opening of said body with its edges received in grooves in the body, forming a chamber communicating with the interior of said body and having a suction opening extending substantially throughout its length for cleaning upholstered furniture and the like; extensions from said body closing the ends of said sleeve; a nozzle mouth part communicating with the interior of said body and having an elongated suction opening; and securing means extending through said nozzle mouth part and in threaded engagement with the extensions of said body, whereby said nozzle mouth part is pivotally secured to said body for converting the nozzle into a rug cleaning nozzle.

AXEL ALBERT FORSBERG.
